CLAIM

The ornamental design for an escutcheon, as shown and described.

DESCRIPTION

FIG. 1 is a perspective view of an escutcheon of the new design;

FIG. 2 is a front elevational view of the escutcheon of FIG. 1;

FIG. 3 is a rear elevational view of the escutcheon of FIG. 1;

FIG. 4 is a left side elevational view of the escutcheon of FIG. 1;

FIG. 5 is a right side elevational view of the escutcheon of FIG. 1;

FIG. 6 is a top plan view of the escutcheon of FIG. 1; and, FIG. 7 is a bottom plan view of the escutcheon of FIG. 1. The portions of the Figures shown in broken lines are not part of the claimed design but are for illustration only.
